UNITED STATES PATENT OFFICE.

SAMUEL CHINN, OF OXNARD, CALIFORNIA.

WHEEL PULLER.

Application filed July 17, 1923. Serial No. 652,045.

To all whom it may concern:

Be it known that SAMUEL CHINN, a citizen of the United States, residing at Oxnard, in the county of Ventura and State 5 of California, has invented certain new and useful Improvements in Wheel Pullers, of which the following is a specification.

This invention relates to certain new and useful improvements in wheel pullers or the 10 like, and aims to provide a device of this kind having simple and durable parts capable of convenient adjustment whereby the device may be employed for use upon various kinds of work.

15 An object of the invention is to generally simplify and improve devices of the above kind whereby the same may meet with all of the requirements for a successful commercial use.

20 Another object is to provide adjustable pulling arms embodying removable swiveled work engaging sections detachably engaged with inner arm sections whereby the desired ones of a plurality of sets of outer 25 sections may be interchangeably employed with the same inner sections of the arms, thereby supplying a tool which will meet the needs of any machine shop and at a minimum cost.

30 With the above general objects in view, and others that will become apparent as the nature of the invention is better understood the same consists in the novel form, combination and arrangement of parts herein- 35 after more fully described, shown in the accompanying drawings and claimed.

In the drawings, wherein like reference characters indicate corresponding parts throughout the several views,

40 Figure 1 is a side elevational view of a wheel remover constructed in accordance with the present invention,

Figure 2 is an end elevational view of the device shown in Figure 1,

45 Figure 3 is a fragmentary detailed view partly in elevation and partly in section and illustrating the swiveled connection between the sections of one of the arms and the adjustable connection between the inner section 50 of the arm and the cross-head of the device,

Figure 4 is an elevational view of a modified form of outer pulling arm section,

55 Figure 5 is a perspective view of one of the retaining bushings of the swivel connection,

Figure 6 is a view similar to Figure 4 showing another form of outer pulling arm section, and

Figure 7 is a view similar to Figure 6 60 of still another form of outer pulling arm section.

Referring more in detail to the drawings, the invention embodies a cross-head or bar 5 which is formed of sufficient size as to 65 withstand the use to which it is put, the form of the bar shown being preferable and in the nature of a flat piece of metal or the like having a central transverse threaded opening 6 for reception of the usual thrust 70 screw 7, the outer end of this screw being formed with an angular head 8 to be engaged by a suitable handle or wrench for facilitating rotation of the same, and the inner end of the screw being pointed or the 75 like as at 9 for proper engagement with the end of the axle or other member which carries the device to be removed. The bar 5 is provided with longitudinal slots extending inwardly from the ends thereof so as to 80 provide the ends in the form of spaced parallel legs 10. Each pair of legs is provided with a longitudinally aligned series of transversely aligned openings 11, and the pulling arms 12 embody inner sections 13 85 having flattened inner ends also provided with a series of longitudinally aligned openings 14 adapted to be selectively aligned with desired pairs of the openings 11 and to then receive a removable pin 15 whereby 90 the arms are attached to the cross-head 5. By means of this construction the pulling arms 12 may be adjusted in a convenient manner toward and away from each other as well as in a direction parallel with the 95 longitudinal axis of the screw 7, which adjustments are essential in accommodating the tool to different kinds of work.

The outer ends of the arm sections 13 are formed with longitudinal internally threaded sockets 16, and the arms 12 also include outer arm sections 17 having their inner ends reduced to provide necks 18 with their free ends enlarged to provide heads 19, the outer ends of the arm sections 17 being of hooked formation as at 20 to engage the article to be removed. The heads 19 are of circular form and adapted to revolvably fit in the inner ends of the sockets 16, a split bushing 21 being placed upon the neck 110 or stem 18 behind the head 19 and removably threaded into the sockets 16 for effec-

tively attaching the arm sections to each other whereby the outer arm sections are freely movable about their longitudinal axes. The bushings 21 are preferably formed of longitudinal half sections as shown at 21' in Figure 5 so that these bushings may be engaged with or disengaged from the necks 18 of the arm sections 17 when desired. For facilitating threading of the bushings 21 into or out of the sockets 16, the outer ends of these bushings are provided with knurled flanges 22, and the arms 10 are preferably provided with transverse pins 23 at the outer sides of the arm sections 13 for preventing swinging movement of the arms toward each other when the operator is placing the puller upon the article to be removed.

In Figure 1 the arm sections 17 are of the preferred form used for pulling or removing the rear wheels of automobiles, and the form of the ends 20 of these sections is such that, if it is not possible to obtain a hold on the brake drum, the sections 17 may be turned as indicated by dotted lines in Figure 2 to engage a spoke of the wheel.

Modified forms of the arm sections 17 are respectively shown at 17^a in Figure 4, 17^b in Figure 6, and 17^c in Figure 7. The arm sections 17^a and 17^b are particularly useful for small gears, such as cam and timing gears on automobiles and the like, while the arm section 17^c is used for heavy work such as fly wheels, etc. The arm sections 17^a, 17^b and 17^c are shorter than the arm sections 17 and have different forms of hook-shaped ends 20, of a smaller size, for these uses. Otherwise, the construction of the arm sections 17^a, 17^b and 17^c are similar to the arm sections 17, each of the same embodying the reduced neck 18 having an enlarged head 19 upon the free end thereof adapted to rotatably fit in the sockets 16 of the sections 13 with which the arm sections 17 are employed. The different forms of outer arm sections are provided in which are thus capable of being interchangeable employed in the sockets 16 of the sections 13 to thereby meet the needs of any machine shop.

From the above description it will be seen that the present device has a very large scope of usefulness, the outer pulling arm sections

being capable of being turned to any desired angle without removing the same from the cross-head, this insures capability of positioning the arm as required in accordance with the various kinds of work to be handled, and the outer arms will automatically turn to accommodate themselves to the proper pulling angle when the pressure is exerted on the screw 7, thereby giving a greater pulling power. By employing interchangeable outer pulling arm sections, the necessity of having a set of complete pullers for each of the uses mentioned, is avoided and the expense thereby minimized.

While the invention has been above noted as primarily adapted for the removal of gears, wheels and the like, it is obvious that the same can be employed as a three-point jack used in bending pipes, straightening crank shafts, cam shafts, etc.

From the foregoing description it is believed that the construction and operation as well as the advantages of the invention will be readily understood and appreciated by those skilled in the art.

Minor changes may be made without departing from the spirit and scope of the invention as claimed.

What I claim as new is:

1. In a wheel puller or the like, a pulling arm including an inner arm section having one end formed for connection with a thrust screw carrying cross-head and having its other end provided with an interiorly threaded socket, an outer pulling arm work engaging section having its inner end reduced to provide a neck with a head upon the free inner end portion thereof adapted for revoluble fit within said socket, and a split bushing threaded in the socket and surrounding the neck forwardly of the head for detachably retaining the outer arm section connected to the inner arm section for free turning movement relative to the latter.

2. A three-point jack comprising a cross-head provided with a central thrust screw and end pulling arms, said pulling arms embodying inner sections and outer sections detachably connected for free rotation relative to each other about their longitudinal axes.

In testimony whereof I affix my signature.
SAMUEL CHINN.
